his Attorney.

Patented July 17, 1928.

UNITED STATES PATENT OFFICE.

HERBERT BERTON, OF LONDON, ENGLAND, ASSIGNOR OF ONE-HALF TO ARTHUR BERTON LIMITED, OF LONDON, ENGLAND.

COMBINED BAG AND CUSHION.

Application filed April 26, 1927, Serial No. 186,655, and in Great Britain January 10, 1927.

This invention has for its object to provide an article which may be used as a bag or as a cushion, pillow or the like, and which, more particularly can be rendered water-
5 proof for either of the said purposes.

According to the invention such a bag and cushion combination consists of a bag made of waterproof material lined at one or both of its sides with a padding covered by ordinary fabric, such as cotton, silk or the like. so that the said padding or paddings form a cushion within a water proof envelope, which is adapted to be turned inside out.

When only one side of the bag is lined with padding and the bag is turned inside out a water proof pocket is formed at the back of the cushion with a front covering of ordinary fabric. If, however, both sides of the bag are padded the turning inside out of the bag produces a cushion, the front and back of which are covered with ordinary fabric while between the two paddings the two sides of the bag form a waterproof pocket.

In order to more fully described the invention reference is had to the accompanying drawings, in which by way of example,

Fig. 1 shows a combined bag and cushion embodying the invention in which one side of the bag only is lined while

Fig. 2 shows the same combination after having been turned inside out.

Fig. 3 is a sectional view of the same combination in the form represented in Fig. 1, and

Fig. 4 a similar view in the form represented in Fig. 2.

Fig. 5 shows in a sectional view a bag lined at both sides, and

Fig. 6 the same when reversed.

In the example shown in Figs. 1 to 4 a waterproof bag of substantially rectangular configuration, is formed by the two sides A and A¹ of waterproof material. A cushion is formed on the inside of the side A (Fig. 3)

45 by a padding B covered by ordinary fabric C, so that the cushion, B, C, is enveloped in a waterproof cover A, A¹. By turning the bag inside out (Figs. 2 and 4) the sides A and A¹ form between them a waterproof pocket D (Fig. 4) while the fabric C now forms the outside front covering of the cushion.

In the modification shown in Figs. 5 and 6 the waterproof bag A, A¹, is lined at both 55 sides with padding B, B¹, covered by ordinary

60 fabric C, C¹ respectively, so that when the bag is turned inside out (Fig. 6) both cushions B, C, and B¹, C¹, are exposed and a waterproof pocket D¹ is formed between them.

In order to provide means for closing the bag a draw-cord E (as shown in the drawings) may be fitted into the seams around the opening of the bag. Any other closure means, such as buttons and button holes, 65 press buttons, hooks and eyes, sliding clasp fasteners, or the like may be employed and a carrying handle may be attached to the combination.

It is obvious that the combination bag and 70 cushion may be of any desired configuration.

This bag and cushion combination is particularly suitable for outdoor use, both for carrying purposes as well as providing damp proof seating accommodation when adjusted in the manner shown in Figs. 1, 3, 4 and 5, for instance in connection with excursions, picnics or the like. As a cushion it prevents the bad effects upon health from damp seats. 75 As a bag in the adjustment shown in Figs. 2, 80 4 and 6, it is suitable for carrying damp or wet objects, as for instance, bathing suits after the bath.

I claim:—

1. A combined reversible bag and cushion, 85 consisting of an open-ended bag made of flexible waterproof material and a padding covered with textile fabric secured to the interior surface of the bag to form a cushion said bag having sufficient capacity to receive 90 said padding, whereby when said padding is exteriorly of the bag a waterproof pocket is presented within said padding, and when said bag is reversed a waterproof covering upon both sides of the padding is afforded. 95

2. A combined reversible bag and cushion, 100 consisting of an open-ended bag made of flexible waterproof material, a padding covered with textile fabric secured to the interior surface of the bag to form a cushion and means for closing the open end of the bag said bag having sufficient capacity to receive said padding, whereby when said padding is exteriorly of the bag a waterproof pocket is presented within said padding, and when 105 said bag is reversed a waterproof covering upon both sides of the padding is afforded.

3. A combined reversible bag and cushion consisting of an open-ended bag made of 110 flexible waterproof material and a padding

- covered with textile fabric secured to one side only of the interior surface of the bag said bag having sufficient capacity to receive said padding, whereby when said padding is 5 exteriorly of the bag a waterproof pocket is presented within said padding, and when said bag is reversed a waterproof covering upon both sides of the padding is afforded.
4. A combined reversible bag and cushion 10 consisting of an open-ended bag made of flexible waterproof material, a padding covered with textile fabric secured to one side only of the interior surface of the bag and means for closing the open end of the bag said bag having sufficient capacity to receive said padding, whereby when said padding is exteriorly of the bag a waterproof pocket is presented within said padding, and when said bag is reversed a waterproof covering upon both sides of the padding is afforded. 15

HERBERT BERTON.
